UNITED STATES PATENT OFFICE

2,518,143

CYLINDRICAL ATTRITION MILL WITH
ROTARY MIDSECTIONKálmán Z. Huszár, Foster, Ohio, assignor to
Wanda Mathews Huszar, Foster, Ohio

Application June 14, 1948, Serial No. 32,927

3 Claims. (Cl. 241—284)

1

This invention relates to an improved grinder and more particularly to a device for grinding sand and similar material.

It is an object of this invention to provide a grinder of the kind to be more particularly described hereinafter in which the material to be ground constitutes also the grinding medium for abrasion with other portions of the mass of similar material contained therein. The method of grinding comprises rotating a mass of material to be ground upon another mass of the same material under pressure, the pressure being provided by the weight of the other material which it is desired to grind.

The grinder to be disclosed herein has been designed primarily for use in the sand and gravel industry. Sand, as found in its natural state, in pits contains approximately 2 per cent of "fines," that is, sand that will pass through a 100 mesh screen. In making concrete, it has been noted that sand containing about 5 per cent "fine" accomplishes the most desirable results. In order to obtain the higher percentage of "fine" sand, either separation and re-assorting or grinding must be resorted to. These methods are quite costly as regards machinery, labor, and time for such a low cost material. Therefore, the grinder of this invention has been devised to accomplish the desired result with a minimum amount of grinding machinery and equipment through which the sand may be readily passed thus affording a considerable saving in the cost of advancing the grade of sand for this use.

Ball mills and pulverizer hammers have been used to grind sand, but the sand to be ground has such an abrasive reaction on the grinder that these mills are subject to and have experienced rapid deterioration. In this mill or grinder, as the material to be ground is used also as the grinding medium, the deterioration caused by reaction of the material to be ground is completely obviated as this reaction is utilized as a source of grinding material.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a top plan view of a grinder con-

2

structed according to an embodiment of my invention.

Figure 2 is a side elevation thereof.

Figure 3 is a vertical section taken on the line 5 3—3 of Figure 1.

Figure 4 is a horizontal section taken on the line 4—4 of Figure 3.

Figure 5 is a bottom plan view of the grinder.

Figure 6 is a fragmentary detailed section 10 showing the attachment of an extension hopper to the stationary body.

Referring to the drawings, the numeral 10 designates generally an improved grinder or pulverizer for reducing the size of sand as taken from the pits to the desirable size for commercial use of the same. Sand as taken from the pit usually contains about 2 per cent of "fines," that is, grains which will pass through a 100 mesh screen. In the commercial use of sand for concrete it has been found that the sand should contain about 5 per cent "fines" for the most desirable result and effect of the concrete. As stated above, it is necessary to employ pulverizers of one kind or another to reduce the large amount of sand to the desirable grain size for the commercial use. Pulverizers and grinders having hammers or ball mills are materially deteriorated in the grinding of sand due to the abrasive effect of the sand on the grinding medium. The principal object of this invention is to employ certain masses of sand as the abrasive medium for reducing the grain size of the main mass of sand to be reduced. I have found that a grinder of the kind to be described hereinafter is suitable economically from all points of view for obtaining the desired results as described above.

The grinder 10 is formed of an exterior frame having vertical supporting posts 11 connected together by horizontal frame members 12. The frame members 12 are fixed to the upper end of the vertical posts 11 for defining the fixed frame work on which the grinder is supported. The grinder includes a cylindrical body 14 having an upper section 15, a bottom section 16 and an intermediate rotating section 17. The upper section 15 is open at the top and bottom and an annular flange as 18 is fixed about the upper open edge for attachment to a hopper or other source of material supply. The intermediate rotating section 17 is open at the top and bottom thereof and the walls of the intermediate section register in alignment with the walls of the upper section 15. The lower section 16 is closed at the bottom thereof by a bottom wall 19 fixed to or formed 50 between the annular walls 20 thereof. The side

walls 20 of the section 16 register in vertical alignment with the walls 21 of the intermediate section 17. The intermediate bracing bars as 22 are fixed between horizontal bars 30 intermediate the length of the vertical frame members 11. An annular bearing member 25 is fixed about the periphery of the intermediate member 17 intermediate the length of the walls 21 thereof.

A bearing member 25 is substantially L-shaped in cross section having a vertical arm 26 which is adapted to be fixed on the side walls 21 and a horizontally extending arm 27 which extends outwardly from the walls. Roller bearings as 28 are rotatably mounted on intermediate frame work of the main frame 11. The bearings 28 are disposed in a vertical plane so that the surface of the bearings engages the lower surface of the horizontal arms 27 of the bearing members 25. The bearings 28 thus rotatably support the intermediate body section 17. Another bearing as 29 is rotatably mounted adjacent the bearings 28. The bearing 29 is disposed in a horizontal plane so that the outer surface of the bearings engage the outer peripheral edge of the horizontal arm 27. Bearings 28 and 29 are supported on the intermediate frame members 30 along the length of the vertical members 11. Rollers 28 and 29 are also mounted on the intermediate frame members 22 so that the bearings for the rotatable section of the grinder will engage the bearing member 25 at equal distances about the periphery thereof.

Angle members as 31 are fixed between the upper frame members 12 and the upper end of the fixed body section 15 for securely attaching and positioning the upper body member in place. Angle bars or brackets as 32 are fixed between the periphery of the lower body section 16 and other intermediate frame members below the supports 30 for the rotating body section.

The bottom wall 19 of the lower section 16 is formed with a discharge opening 34 therein. A bearing 35 which includes a depending bolt 36 extends downwardly from the lower surface of the bottom wall 19. A lever 37 is pivotally mounted intermediate its length on the pivot bolt 36 and a valve member as 38 is fixed on one end of the lever 37. The valve member 38 is adapted to close the opening 34 through the bottom wall 19 for retaining a mass of material within the body of the grinder.

A truncated conical guide member 40 is fixed on the frame which supports the grinder below the discharge opening 34. The funnel 40 is spaced below the discharge opening 34 and the valve 38. The funnel 40 is fixed relative to the frame by being attached to the vertical frame members 11 by suitable angle bars 41. The funnel 40 is adapted to guide the discharged sand or material from the lower end of the grinder onto the upper stretch 42 of a flexible belt or conveyor which is positioned below the grinder 10. The free end of the conveyor is adapted to be positioned within the confines of the frame work 11 so that the sand discharged from the grinder 10 will be carried away to a suitable place for removal or storage.

In Figure 6, there is shown an extension hopper which is adapted to be mounted on the upper end of the fixed body section 15. The extension hopper 50 is formed of a cylindrical body open at both ends thereof and having walls 51 which are adapted to register in vertical alignment with the vertical walls of the upper fixed body section 15. An annular flange as 52 is fixed

to or formed on the lower end of the extension hopper 50 and is adapted to abut the annular flange 18 about the upper end of the upper body section 15.

An annular grooved guide member as 60 is fixed to or formed about the periphery of the rotating body section 17. The grooved member 60 constitutes a pulley concentric to the body section 17 and fixed about the outer wall thereof. The grooved member 60 is fixed as shown in Figure 3 to the vertical arm of the bearing member 25. A motor as 61 is fixed on the frame members 11 by a base plate 62 which is secured to the motor and is attached by suitable fastening means to the intermediate frame members 30 and 61. A pulley 64 is mounted on the shaft of the motor 61 and a belt as 65 is engaged about the pulley 64 and around the grooved guide member 60 carried by the rotating section 17. In this manner the rotating member 17 may be rotated relative to the fixed sections 15 and 16 by the energization of the motor 61.

In the use and operation of the grinder 10 the body thereof is substantially filled with sand so that a mass of sand is contained within each of the sections 15, 16 and 17 thereof. When the motor 61 is energized the intermediate body section 17 will be rotated relative to the adjacent body sections 15 and 16. The rotation of the walls 21 will then effect the rotation of the mass of sand contained therein. The gravitational force of the sand within this body section and the force of the sand exerted downwardly on this mass by the mass of sand above it in the body section 15 will effect the adhesive connection between the sand in the rotating section and the walls 21. The rotating mass in the rotating section 17 will then be in abrasive contact with the mass of sand in the adjacent sections. The abrasive effect of the rotating mass of sand will result in the grinding of the masses of sand at the contact of the rotating and fixed masses. In this manner the sand to be ground is actually ground by the adjacent masses of the same sand. In other words, the material to be ground is effectively the grinding medium. During the grinding operation wherein the intermediate body section 17 is rotated relative to the fixed body sections 15 and 16, the valve 38 is adjusted to control the rate of discharge through the opening 34, thus producing the degree of grinding desired. The grinding operation is continuous, the valve 38 may be moved from its position below the opening 34 by movement of the handle 66 on the opposite end of the lever 37.

I claim:

1. An improved grinder of the kind described comprising a supporting frame, a pair of stationary and axially spaced apart vertical walled concentric cylindrical members fixed on said frame, an open ended cylindrical member between said spaced apart members and concentric thereto all three cylindrical members being of substantially the same diameter, and a closure plate secured to the bottom of the lower of said members, roller means on said frame engaging the periphery of the latter cylindrical member for rotatably mounting said latter cylindrical member on said frame, driving means carried by said frame engaging said rotating member for rotation relative to said spaced apart members.

2. An improved grinder of the kind described comprising a frame, a pair of vertical walled stationary and axially spaced apart concentric cylindrical members fixed to said frame, a closure

plate secured to the bottom of the lower of said pair of members, an open ended vertical walled cylindrical member disposed between said pair of members in end confronting relation thereto, all three cylindrical members being of substantially the same diameter, roller means on said frame engaging the periphery of said open ended member for rotatably mounting said latter member on said frame, driving means on said frame engaging said rotatable cylindrical member for causing rotation thereof, a discharge opening formed through said closure plate, and a valve carried by said plate adapted to selectively obstruct flow of material through said discharge opening.

3. An improved grinder of the kind described comprising a frame, a top vertical walled stationary cylindrical member fixed on said frame, a bottom vertical walled cylindrical member fixed on said frame spaced axially downwardly from, and disposed concentrically with, said top member, a closure plate sealing the lower end of said bottom member, a vertical walled intermediate cylindrical member disposed between said top and bottom members, all three of said cylindrical members being of substantially the same diameter, an outwardly extending annular flange on said intermediate member, first roller means on said frame engaging under said flange, second roller means

10

15

on said frame engaging the peripheral edge of said flange whereby said intermediate member is rotatably supported on said frame, driving means on said frame engaging the periphery of said intermediate member for effecting rotation of the latter, a discharge opening formed in said closure plate, and valve means carried by said plate and adapted to regulate the flow of material through said opening.
